LATCH MECHANISM

John P. Tarbox, Philadelphia, Pa., assignor to
 Edward G. Budd Manufacturing Company,
 Philadelphia, Pa., a corporation of Pennsylvania

Application August 14, 1925. Serial No. 50,170

4 Claims. (Cl. 292—337)

My invention relates to automobile door latches of that class the purpose of which is to enlarge the range of vision through the window of the door. Automobile door windows are commonly movable up and down to open and close the window. The windows are preferably made as wide as possible to secure the maximum range of vision therethrough. But the fact that space has to be provided for the usual transversely extending latch operating spindle limits the width of the window. In the old carriage doors and later in the automobile doors this spindle was moved as closely as possible to the jamb face of the door to get a maximum in width, and within recent dates these latch mechanisms have been devised to circumvent the path of movement of the window, the operating mechanism passing without the borders or without the path of the window glass in any position and returning again within the transversely projected borders of the path. With the making of this latter invention, the old type of through-spindle was departed from though its equivalent was used in some cases. My invention has to do particularly with a construction by means of which the old type of spindle can be used, and the simplicity and sturdiness of the old type of latch and very low cost of manufacture are one and all retained.

According to my invention I provide in connection with the jamb rail of the door an exterior projection from its jamb face, and carry the usual latch operating spindle transversely of the door through this projection. The projection itself I utilize as an element of a dove-tail formed by it and coacting dovetail formations on the door post.

The best form of my invention now known to me is shown in the accompanying drawings. Of these Figure 1 is a perspective view of a latch per se of the latch mechanism detached from the door.

Fig. 2 is a perspective view of the door and portions of the mechanism including the latch operating spindle, the main body of the door being broken away to effect a showing on the large scale;

Fig. 3 is a horizontal section of this embodiment in a plane including the axis of the latch operating spindle, and

Fig. 4 is a perspective view of the coacting door post and latch keeper.

Fig. 5 is a small size elevation showing modified arrangement of operating handles.

The door in which my invention is embodied is a door of the modern steel construction. Its

jamb rail 10 is of pressed steel having a cross section in the shape of a double Z. The outermost branch 11 of this jamb rail extends outwardly of the jamb face of the rail and constitutes the over-lap of the door which covers the space between the jamb rail and the door post 12 when the door is closed, as most clearly appears in Fig. 3. This outermost branch 11 also carries the outer paneling 13, the edges of the latter being bent and pinched over and welded thereto. In the angle between the outermost main body 14 of the jamb rail and the intermediate branch 15 is secured an angle member 16 which is positioned in such manner that it cooperates with the branch 15 to form therewith a glass run channel 17. The detachable window glass 18 is thus provided with a run-way or guide-way, which latter is lined on its inner surface with felt 19 for a purpose well understood in the art.

Secured in the angle between the innermost main body portion 20 of the Z section jamb rail and the latch board 21 and carried from the inner branch 22 of the Z section of the rail is the main body of a latch mechanism designated generally 23. This latch mechanism embodies a lock plate 24, a sliding latch bolt 25, and an interior oscillatable latch operating handle 26 pivoted at 27 and operatively connected with the latch bolt through its engagement with the arm 28 of the bell crank 29, which latter is also mounted on the pivot 27. In addition to these principal elements of the latch mechanism I have provided an exteriorly operating handle 30 which is connected with the free end of the arm 31 of the bell crank 29 through the arm or lever 32. I preferably provide a loose connection between the free ends of the arms 31 and 32 by means of a pin 33 and a slot 34 provided respectively on either one or the other of these arms.

The sliding bolt 25 is arranged to slide through an opening provided in the innermost main body portion 20 of the jamb rail 10. A housing 35 is provided for this sliding bolt, which housing is provided with a main body portion 36 having laterally turned tabs or ears 37 at each of its ends, these ears being secured to the latch plate 24 preferably by rivets 38. This casing or housing 35 has a cut-out portion 39 at the top thereof and a similarly cut-out portion at the bottom thereof for a purpose to be described immediately hereinafter. The bolt 25 is itself provided with a cut-out portion 40 intermediate its ends and the base 41 of this cut-out portion is provided with a slot 42. As most clearly appears in Fig. 1 the slot 39, while in vertical alignment with the slot 110

42, is of considerably greater extent. Secured in any suitable manner to the latch casing 24 or to the housing 35 or to both is a pin 43 which serves as the back-stop for a spring 44 which latter tends to normally keep the sliding latch in forward or projected position.

As has already been stated the latch mechanism includes the interior operating handle 26 and the bell crank 29 both of which are pivoted 10 on the pin 27 which latter is secured to the latch plate 24. By virtue of the bottommost slot 39 in the bolt housing 35 and the slot 42 in the bolt itself it becomes possible to insert the bell crank arm 28 and the lower portion of the handle 26 15 therethrough. When these are inserted through the slots 39 and 42 and mounted for pivotal movement on the pin 27, as is best shown in Fig. 1, it will be seen that by lifting the arm 31 of the bell crank 29 the arm 28 thereof operates to engage 20 the rear wall of the slot 40 of the bolt 25 to move the latter into retracted position. During this operation it is, of course, evident that the operating handle 26 is in no manner disturbed since the bell crank 29 is independent 25 thereof. However, by pulling the handle 26 rearwardly the arm 28 is engaged thereby and it in turn engages the rear wall of the slot 40 of the bolt 25 to retract the latter in a manner similar to that described when the arm 31 of the bell 30 crank 29 is raised. In this case, however, the latch operating handle 26 moves in conjunction with the inside operating handle 30, this because the latter is connected through the lever 32 with the arm 31 of the bell crank 29.

35 The most important feature of this invention, however, is the provision I have made for permitting maximum vision through the window of the door. Instead of passing the spindle 45 of the handle 30 transversely of the door but within 40 the plane of the jamb face of the door, I have provided that this spindle 45 may be positioned without the plane of the jamb face. In order that this be accomplished, I have provided a projection 46 in the nature of a transversely extending 45 offset in the face of the outermost main body portion 14 of the door rail. This is most clearly shown in Fig. 2. The spindle 45 is passed through this offset projection and is journaled in the space between the glass run channel 17 and the outer 50 wall of the offset. When journaled in this manner the spindle 45 passes through the over-lap 11 of the door and lies without the jamb face thereof. I have found it preferable to provide that this offset portion of the jamb face be positioned 55 below the lower face of the bolt 25, this for a purpose which will be presently described.

The post 12 as shown in this instance is an intermediate post of the type adapted to receive the jamb faces of doors at opposite sides thereof. 60 Only one such door is shown in this case though it is to be understood that another door is to be provided and the opposite face of the post constructed and equipped accordingly. This post carries a latch keeper 47 of the usual form in line 65 with the sliding bolt 25. The keeper is provided with stepped faces 48 and 49 for the purpose which is well understood in the art. Immediately below the keeper and in line with the offset portion 46 in the jamb face of the door the body of the sheet metal post 12 is inwardly offset as indicated at 50. This offset is in the nature of a grooved recess complementally formed with respect to the transversely extending projection 46 in the jamb face of the door and is adapted to 70 receive the offset projection 46 from the jamb 75

face of the door as is most clearly shown in Fig. 3. When the door is in closed position, there is effected by virtue of the coaction of the complementally formed offsets 46 and 50 an interfitting connection between the door and post which 80 renders unnecessary the provision of male dove-tail members in addition to the latch mechanism for securing proper alignment of the door in its door opening. Yielding engaging walls in any of the well known dove-tail forms may be provided in lieu of the fixed walls of the offsets 50. Appropriate taper and clearances may be provided as common in dove-tail structures.

The operation of my latch and the coaction and operating between the several parts of the door and the post will now be apparent from the foregoing description. When the door is to be opened, either one of the handles 30 or 26 may be operated to retract the bolt 25 so that it is disengaged from the keeper face 49 whereafter the door may be opened. By reason of the fact that the door is provided with an offset projection formed complementally with respect to the groove formed in the post to receive the same, they constitute or serve the purpose of the usual dove-tail for aligning the door with respect to the jamb.

The handles 30, as disclosed in Figs. 1 to 4, are of the one-armed lever type, the arms projecting in each case away from the post so that they will not interfere with each other by reason of the close proximity of the spindles to each other. In Fig. 5 is shown an alternative arrangement according to which either the latch mechanisms bodily or the spindles and operating mechanism 105 only are vertically displaced on the adjacent doors whereby double-armed operating levers or handles of the usual type may be used without interference, for the spindles are by this arrangement moved farther apart.

The spindle is in each case journaled in the offset 46 which has a semi-cylindrical form and a depth to accommodate the full diameter of the spindle. The spindle 45 is held therein by the glass run channel 17, as shown, but it is to be 120 understood that any other means of securing the spindle in the bearing or any special bearing desired may be provided.

Where I have used in the following claims the expression "an extensible portion of substantially the full width of the body of the door", or a similar expression, it has reference more particularly to the relative extent of the door and the extensible portion or sliding window at the latch side of the door with which my invention 125 is more particularly concerned.

Other embodiments of my invention will occur to those skilled in the art upon the disclosure of this one and the understanding of its generic spirit which the disclosure provides. Such modifications are intended to be defined by the terms 130 of the appended claims.

What I claim is:

1. In combination, an automobile door having a pressed metal jamb rail, having an integral outward offset in its jamb face together with a latch mechanism connected with said door and provided with interior and exterior latch operating devices inter-locked by means housed in said offset.

2. In combination, an automobile door having a jamb rail provided with an integral exterior projection on its jamb face, a latch mechanism connected with said door interiorly thereof having interior and exterior operating members carried 145 150

- by said door and operatively connected together by means passing through said projection, and a door post having a jamb face juxtaposed to said rail and inwardly offset to accommodate said projection.
3. In combination, an automobile door having a jamb rail provided with an integral exterior projection on its jamb face, a latch mechanism connected with said door interiorly thereof having interior and exterior operating members carried by said door and operatively connected together by means passing through said projection, and a door post provided with walls coacting with the opposite sides of said projection to constitute with it an interfitting connection between the door and post.
4. In combination, an automobile door comprising an extensible portion substantially of the full width of the body of the door, and a jamb rail of pressed metal constituting a part of the body of the door and having an integral outwardly projecting portion extending into the space between the jamb face and the door post, a latch mechanism connected together by means supported through the intermediary of said outwardly projecting portion.
